[57] CLAIM

The ornamental design for a water closet, as shown and described.

DESCRIPTION

FIG. 1 is a perspective view of a water closet showing our new design;

FIG. 2 is a top plan view thereof;

FIG. 3 is a front elevational view thereof;

FIG. 4 is a left side elevational view thereof; and

FIG. 5 is a right side elevational view thereof.

The broken line representation of fitting holes in FIGS. 1, 2 and 4 are for purposes of illustration only.
